(57) **CLAIM**

The ornamental design for a cap for securing articles, as shown and described.

DESCRIPTION

FIG. 1 is a perspective view of a cap for securing articles, constructed in accordance with the present invention;

FIG. 2 is a left side view of a cap for securing articles as shown in FIG. 1;

FIG. 3 is a right side view of a cap for securing articles as shown in FIG. 1;

FIG. 4 is a top view of a cap for securing articles as shown in FIG. 1;

FIG. 5 is a front view of a cap for securing articles as shown in FIG. 1; and,

FIG. 6 is a bottom view of a cap for securing articles as shown in FIG. 1.

The carpenter's pencil shown in broken lines in FIG. 1 is environmental matter, and forms no part of the claimed design. The broken lines that are shown along the edges of the visor, the headband, the size adjustment opening, on either side of the gore seams, on the interior surface of the crown, and along the edge of the article-holding structure on both the interior and exterior surfaces, illustrate stitching and are a part of the claimed design.
